UNITED STATES PATENT OFFICE.

EDWARD B. HINE, OF LONGMEADOW, MASSACHUSETTS, ASSIGNOR TO GILBERT & BARKER MANUFACTURING COMPANY, OF WEST SPRINGFIELD, MASSACHUSETTS, A CORPORATION OF MASSACHUSETTS.

RESILIENT ACTUATOR.

1,413,272.

Specification of Letters Patent.

Patented Apr. 18, 1922.

Original application filed April 30, 1921, Serial No. 465,789. Divided and this application filed December 7, 1921. Serial No. 520,613.

To all whom it may concern:

Be it known that I, EDWARD B. HINE, a citizen of the United States, residing at Longmeadow, in the county of Hampden 5 and State of Massachusetts, have invented new and useful Improvements in Resilient Actuators, of which the following is a specification.

This invention relates to improvements in 10 mechanical devices in the nature of a resilient actuator, such as may be used as a yieldable arm or abutment on one of two movable members which intermittently engage to transmit motion from one to the other.

15 While the invention is capable of general application, it finds one advantageous use as part of the actuating mechanism for a register of the general type disclosed in my copending application Serial No. 465,789 20 filed April 30, 1921, of which this application is a division.

The object of the invention is to provide 25 a resilient arm or abutment, which is adapted to be located in the path of a reciprocable member and is capable of being engaged thereby on each stroke thereof, characterized in that the arm is more readily yieldable when engaged on one stroke of the member than on the other.

30 Other objects and advantages will appear in the following description and in the illustrative embodiment of the invention in the accompanying drawings, in which,—

Fig. 1 is a cross-sectional view of a register with which a resilient actuator, embodying my invention, is associated;

Fig. 2 is a fragmentary elevational view showing the interior of the register; and

Fig. 3 is a sectional view, taken on the 40 line 3—3 of Fig. 1, showing the resilient actuator.

The invention is herein shown as associated with a register which is operated by the reciprocating piston rod of a measuring and dispensing pump. The register and pump mechanism are disclosed herein merely by way of illustrative example of one of the many uses to which the invention may be put and the invention is entirely independent 45 of the particular details of the register and pump structure.

The latter will first be described with particular reference to Figs. 1 and 2. The

register casing consists of two members 5 and 6, the former having a peripheral flange 55 7 secured to the latter by screws 8. The outer face of member 5 is usually graduated as a dial and movable over this face is a pointer 10 fixed to the outer end of a shaft 11, which is rotatably mounted in and extends between the members 5 and 6. On shaft 11 is fixed an escapement wheel 12 and cooperating therewith is an oscillatable operating lever 13, which is fixed intermediate its ends to a shaft 15 rotatably mounted in a hub 16 extending rearwardly from the casing member 55. The free ends of lever 13 carry pins 16' which alternately engage the teeth of the escapement wheel 12. The arrangement is such that one pin 16' enters a tooth space 17 just before the other pin leaves another tooth space so that at no time is wheel 12 released for free movement in a forward (clockwise) direction. Retrograde movement, as far as a predetermined point may be accomplished manually by turning a handle 18. The teeth 19 have radial faces 20 and inclined faces 21, like ratchet teeth, to permit retrograde but not allow forward movement. One tooth, as 22, has in its inclined face a shoulder 23 to limit the retrograde movement of wheel 12 and an adjacent tooth 24 is rounded, as at 25, to aid in allowing the pin 16' to lodge against shoulder 23 and perform its function.

The register casing is secured by screws 35 to a part *c* of the casing of a measuring and dispensing pump, *b* indicating another part of such casing. 29 indicates a member 90 reciprocable with the piston of the pump which carries one or more projecting pins or abutments 28, any one or more of which are adapted to engage an arm or abutment on shaft 15 for the purpose of rocking lever 95 13 in one direction, return movement of the latter being effected by a spring 26. Any one of the members 28 may move beyond the arm on shaft 15 and will therefore reengage the arm on the return stroke tending to move 100 lever 13 in a direction opposite to that of the first movement. The lever 13, however, after the movement caused by an upstroke of pin 28, was moved in a reverse direction by spring 26 and is prevented from moving further in the latter direction by reason of the

upper pin 16' engaging wheel 12. Therefore, the arm on shaft 15 must yield readily to permit the downward movement of pin 28. Also the stroke of pin 28 being greater than the stroke, or degree of oscillation, of lever 13, it is desirable that such arm be arranged to yield on an upstroke of pin 28 after lever 13 has moved the required distance, although the arm should not yield so readily as to prevent lever 13 being moved the full distance.

To meet these conditions, I provide, as the arm or abutment on shaft 15, a resilient actuator which is preferably constructed as best shown in Fig. 3. The arm, or abutment, described consists of a projection 27 which consists of the free end of a piece of flat spring material 30. The latter is fastened at its other end by inserting it in a slot 31 (Fig. 1) formed in the ends of shaft 15 and a collar 32 fixed to the latter. From its fixed end, the member 30 projects radially outwardly from collar 32 and is then bent backwardly upon itself, extending in substantially parallel relation thereto and tangentially to upper portion of collar 32 beyond the latter, where it is again bent upon itself in parallel relation and extends across, beyond and substantially tangentially to the lower portion of collar 32.

The practical result of this construction is to provide a projection 27 which is yieldable when engaged on either side by another projection, such as 28 but much less readily yieldable in one direction than the other. Thus on the upstroke of member 28, it will engage projection 27, but the latter tends to bend from its point of contact with collar 32 and offers considerable resistance to the projection 28. It is intended that, under such circumstances, the projection will not yield to any substantial degree until the lever 13 has been moved, but as soon as the latter is arrested, it can yield, if necessary, to permit projection 28 to pass it. On a return stroke of the latter, the projection 27 yields readily to permit projection 28 to pass it, because it moves away from the collar and can open up and deflect the hitherto parallel portions of member 30 into diverging relation.

The invention has been disclosed herein, in an embodiment at present preferred, for illustrative purposes, but the scope of the invention is defined by the appended claims rather than by the foregoing description.

What I claim is—

1. The combination with two members both of which are movable back and forth and one of which is adapted to engage and move the other, of an arm on one of said members for engagement by the other, said arm being resilient and arranged to yield more readily when engaged in one direction than the other.

2. In combination, a driven member movable back and forth between fixed limits, a driving member movable back and forth through greater limits, an arm on one of said members with which the other member is adapted to engage and pass beyond on one stroke and reengage and pass beyond on a return stroke, said arm being yieldable when engaged on the first stroke after the driven member has been moved to permit the driving member to pass and more readily yieldable when engaged on the return stroke.

3. In combination, a driven member movable back and forth between fixed limits, yieldable means for moving it in one direction and holding it at one of its limits, a driving member movable back and forth through greater limits and by which on one stroke the driven member is moved in the other direction, and a resilient arm on one of the members adapted for engagement by the other to move the driven member, said arm being yieldable after the driven member has moved to the other of its limits to permit the driving member to pass beyond and being more readily yieldable when reengaged on the return stroke of the driving member.

4. The combination with a movable member, of abutments provided on opposite sides thereof, a resilient element fixed to said member at one end, extending across and beyond one of said abutments and bent backwardly to extend across the other abutment with the other end of the element projecting from the latter.

5. The combination with two movable members of a resilient actuator on one end thereof having an arm portion adapted to be engaged and moved by the other member, said portion projecting to one side of its member and having another portion forming an extension thereof projecting to the opposite side of said member and a third portion connecting the second portion to the member, and an abutment provided on the member to be engaged by the actuator when moved in one direction and engaged at a point between the first and second portions, said actuator when engaged in the opposite direction moving the first and second portions away from said abutment.

6. A resilient actuator, comprising, a non-resilient element adapted to be fixed to a movable member, and a resilient member fixed at one end to said element and having a portion projecting from one side thereof, said resilient member being bent backwardly upon itself and to form a second portion which extends across and to the opposite side of the element and contacts with the latter intermediate its ends, said resilient member being again bent backwardly upon itself to form a third portion which extends across said element and projects from the first-named side of said element contracting with

the latter intermediate its ends at a point on said element substantially opposite to that at which the second portion contacts.

7. A resilient actuator, comprising, a member adapted for attachment to a movable member, and a resilient element bent into substantially the shape of a **U** with one side arm of the **U** extended and bent backwardly

upon itself to form a second reversely located **U** which includes the first **U**, one end 10 of said element being fixed to the first named member.

In testimony whereof I have affixed my signature.

EDWARD B. HINE.
